UNITED STATES PATENT OFFICE.

HARRY F. BUSHONG, OF KALAMAZOO, MICHIGAN, ASSIGNOR TO KALAMAZOO LOOSE LEAF BINDER COMPANY, OF KALAMAZOO, MICHIGAN, A CORPORATION.

TEMPORARY BINDER OR LOOSE-SHEET HOLDER.

No. 890,019.

Specification of Letters Patent.

Patented June 9, 1908.

Application filed July 31, 1905. Serial No. 272,033.

To all whom it may concern:

Be it known that I, HARRY F. BUSHONG, a citizen of the United States, residing at Kalamazoo, in the county of Kalamazoo, State of Michigan, have invented certain new and useful Improvements in Temporary Binders or Loose-Sheet Holders, of which the following is a specification.

This invention relates to improvements in temporary binders or loose sheet holders.

It is particularly adapted to the style of binder illustrated and described in my application for Letters Patent filed August 5, 1904, Serial Number 219,624, and is a modification and in some respects an improvement on that structure, although it is applicable for use in other relations.

The objects of this invention are, first, to provide an improved temporary binder or loose sheet holder which may be very quickly and easily adjusted to receive or remove one or more sheets, as desired. Second, to provide an improved temporary binder or loose sheet holder adapted to securely retain any number of sheets or leaves, from one to its maximum capacity, which may be quickly adjusted to receive or to permit the removal of any number of sheets or leaves.

Further objects, and objects relating to structural details, will definitely appear from the detailed description to follow.

I accomplish the objects of my invention by the devices and means described in the following specification.

The invention is clearly defined and pointed out in the claims.

A structure embodying the features of my invention is fully illustrated in the accompanying drawing forming a part of this specification, in which:

Figure 1 is a plan view from the rear or outside of my improved temporary binder or loose sheet holder in its open position, the rear walls of the cover being removed. Fig. 2 is an enlarged detail transverse sectional view taken on a line corresponding to line 2 2 of Fig. 1, showing structural details of the adjusting mechanism. Fig. 3 is an enlarged detail view taken on line 3 3 of Fig. 2. Fig. 4 is an enlarged detail view taken on a line corresponding to line 4 4 of Fig. 1.

In the drawing the sectional views are taken looking in the direction of the little arrows at the ends of the section lines and simi-

lar letters of reference refer to similar parts throughout the several views.

Referring to the drawing, the covers A A are formed with chambers therein to receive the adjusting mechanism of the binder. A pair of clamping bars F are pivotally secured to the covers by suitable hinges, as f. These bars are preferably of the form described in my co-pending application heretofore referred to. Binding cords C are arranged through the bars and are secured at one end to the cross-bar B. The binding cords are preferably formed of a single piece, which is looped about the block a at the inner end of the cover A'. This block is preferably curved, so that the binding cord freely adjusts itself over it, thereby maintaining an equal tension upon the cord and clamping bars throughout their length.

The bar B is adjusted by means of the longitudinally arranged threaded shaft D, which is supported in suitable bearings d within the cover A. This shaft is controlled by a suitable key, as d'. The bar is connected to the shaft by means of the threaded half-nut or block b which is adjustably secured to the bar. (See Figs. 2 and 3.) The threaded block b is held into engagement with the screw shaft by the cam e, which is slidably mounted upon the rockshaft E. The cam e is arranged in a suitable slot in the bar B, so that as the bar is shifted the cam is carried back and forth upon the rockshaft. The rockshaft is preferably rectangular in cross-section, to engage the cam.

A finger piece or lever E' for manipulating the rockshaft E, is arranged through a suitable opening a' in the cover wall A''. By manipulating the rockshaft the cam e is thrown into or out of engagement with the block b, causing it to engage or release the shaft, thereby connecting or disconnecting the bar B thereto.

When it is desired to open the binder, the lever E' is manipulated to release the block from the shaft, thereby freeing the bar B and allowing the clamping bars to be drawn apart against the tension of the springs B'' which are secured to the bar B. In closing the clamping means, the springs B'' retract the bar B to take up the slack in the binding cords. The lever E' is then manipulated to throw the block into engagement with the screw, and by means of the key the clamping

bars are drawn tight upon the leaves. In order to enable the use of longer return springs than would otherwise be practical, the bar B is provided with inwardly projecting arms B', to which the springs are attached, as clearly appears in Fig. 1.

By arranging the parts as I have illustrated and described, I am enabled to clamp the leaves very securely and at the same time I provide a means by which the clamping means may be quickly and easily adjusted for removing or inserting sheets.

I have illustrated and described my improved temporary binder or loose sheet holder in detail in the form preferred by me on account of its structural simplicity and convenience in operation. I am, however, aware that it is capable of considerable variation in structural details without departing from my invention.

Having thus described my invention, what I claim as new and desire to secure by Letters Patent, is:

1. The combination of the covers; clamping bars pivotally connected to said covers; a binding cord connected to one of said covers and arranged through said clamping bars; a cross-bar to which the ends of said binding cords are secured, arranged in the opposite cover; a screwthreaded shaft for adjusting said bar; a threaded block adjustably secured to said cross-bar for securing the same to said shaft; a rockshaft arranged parallel with said threaded shaft; a cam carried by said cross-bar adapted to throw said threaded block into engagement with said threaded shaft, controlled by said rockshaft; and a spring connected to said cover and to said cross-bar for retracting the same, for the purpose specified.

2. The combination of the covers; binding cords connected to one of said covers; a cross-bar to which the ends of said binding cords are secured, arranged in the opposite cover; a screwthreaded shaft for adjusting said cross-bar; a threaded block adjustably secured to said cross-bar for connecting the same to said shaft; a rectangular rockshaft arranged parallel with said threaded shaft; a cam carried by said cross-bar adapted to throw said threaded block into engagement with said threaded shaft, slidably mounted on said rockshaft; and a spring connected to said cover and to said cross-bar for retracting the same, for the purpose specified.

3. The combination of the covers; binding cords connected to one of said covers; a cross-bar to which the ends of said binding cords are secured, arranged in the opposite cover; a screwthreaded shaft for adjusting said cross-bar; a threaded block adjustably secured to said cross-bar for connecting the same to said shaft; a rockshaft arranged parallel with said threaded shaft; a cam carried by said cross-bar adapted to throw said

threaded block into engagement with said threaded shaft, controlled by said rockshaft; and a spring connected to said cover and to said cross-bar for retracting the same, for the purpose specified.

4. The combination of the covers; binding cords connected to one of said covers; a cross-bar to which the ends of said binding cords are secured, arranged in the opposite cover; a screwthreaded shaft for adjusting said cross-bar; a threaded block adjustably secured to said cross-bar for connecting the same to said shaft; a rockshaft arranged parallel with said threaded shaft; a cam carried by said cross-bar adapted to throw said threaded block into engagement with said threaded shaft, controlled by said rockshaft; and means for retracting said cross-bar when released from said screw shaft, for the purpose specified.

5. The combination of the covers; clamping bars pivotally connected to said covers; binding cords connected to one of said covers and arranged through said clamping bars; a cross-bar to which the ends of said binding cords are secured, arranged in the opposite cover; a screw shaft for adjusting said bar; a threaded block adjustably secured to said cross-bar for securing the same to said shaft; means for shifting the said block into and out of engagement with said screw shaft; and a spring connected to said cover and to said cross-bar for retracting the same when released from said shaft, for the purpose specified.

6. The combination of the covers; clamping bars pivotally connected to said covers; binding cords connected to one of said covers and arranged through said clamping bars; a cross-bar to which the ends of said binding cords are secured, arranged in the opposite cover; a screw shaft for adjusting said bar; a threaded block adjustably secured to said cross-bar for securing the same to said shaft; means for shifting the said block into and out of engagement with said screw shaft; and means for retracting said cross-bar when released from said shaft, for the purpose specified.

7. The combination of the covers; binding cords connected to one of said covers; a cross-bar to which the ends of said binding cords are secured; a screwthreaded shaft mounted on the other cover for adjusting said cross-bar; a threaded block adjustably secured to said cross-bar for connecting the same to said shaft; means for shifting said block into and out of engagement with said screw shaft; and springs connected to said cover and to said cross-bar for retracting the same when released from said shaft, for the purpose specified.

8. The combination of the covers; binding cords connected to one of said covers; a cross-bar to which the ends of said binding cords are secured; a screwthreaded shaft mounted

on the other cover for adjusting said cross-bar; a threaded block adjustably secured to said cross-bar for connecting the same to said shaft; means for shifting said block into and out of engagement with said screw shaft; and means for retracting said cross-bar when released from said shaft, for the purpose specified.

9. The combination of the covers; clamping bars pivotally connected to said covers; a binding cord connected to one of said covers and arranged through said clamping bars; a screw shaft for adjusting said binding cord; means for detachably connecting said binding cord to said shaft; and a spring connected to said cover and to said cord for retracting the same when released from said shaft, for the purpose specified.

10. The combination of the covers; clamping bars pivotally connected to said covers; a binding cord connected to one of said covers and arranged through said clamping bars; a screw shaft for adjusting said binding cord; means for detachably connecting said binding cord to said shaft; and means for retracting said binding cord when released from said shaft, for the purpose specified.

11. The combination with the covers of a binding cord; a screw shaft for adjusting said binding cord; means for detachably connecting said binding cord to said shaft; and a spring for retracting said binding cord when released from said shaft; for the purpose specified.

12. The combination with the covers of a binding cord; a screw shaft for adjusting said binding cord; means for detachably connecting said binding cord to said shaft; and means for retracting said binding cord when released from said shaft, for the purpose specified.

13. The combination of the covers; clamping means; means for adjusting said clamping means; means for detachably connecting said clamping means with the adjusting means therefor; and a spring for retracting said clamping means when released from said adjusting means, for the purpose specified.

14. The combination of the covers; clamping means; means for adjusting said clamp-

ing means; means for detachably connecting said clamping means with the adjusting means therefor; and means for retracting said clamping means when released from said adjusting means, for the purpose specified.

15. The combination with the covers, of leaf clamping means; an adjusting mechanism for said leaf clamping means; means for detachably connecting said leaf clamping means with said adjusting mechanism therefor whereby the leaf clamping means may be released from the adjusting mechanism therefor to permit of rapid opening of the leaf clamping means independently thereof, and connected to said adjusting mechanism for closing said leaf clamping means.

16. The combination with the covers of binding cords; means for adjusting said binding cords; and means for detachably connecting said binding cords with said adjusting means therefor, whereby said binding cords may be released from the said adjusting means to permit the rapid opening of the binder independently thereof said detachable means being connected to said adjustable means for closing the binder.

17. In a device of the class described, the combination of separate cover sections, clamping members located between and pivotally connected to the respective sections, said members being provided with transverse apertures, a flexible member secured by one end to one of the sections and passing through the apertures, means mounted on the other section to which the free end of the flexible member is secured, means engaging the last said means for operating the same to tighten the flexible member, and means for throwing the operating means out of engagement with the tightening means to permit the covers to be readily separated.

In witness whereof, I have hereunto set my hand and seal in the presence of two witnesses.
